UNITED STATES PATENT OFFICE.

EDWIN P. McLANE, OF MOUNT CARMEL, CONNECTICUT.

GAME-BOARD.

SPECIFICATION forming part of Letters Patent No. 487,447, dated December 6, 1892.

Application filed May 31, 1892. Serial No. 434,856. (No model.)

To all whom it may concern:

Be it known that I, EDWIN P. McLANE, of Mount Carmel, in the county of New Haven and State of Connecticut, have invented a new 5 Improvement in Game-Boards; and I do hereby declare the following, when taken in connection with accompanying drawings and the letters of reference marked thereon, to be a full, clear, and exact description of the same, 10 and which said drawings constitute part of this specification, and represent, in—

Figure 1, a plan view of a game-board constructed in accordance with my invention; Fig. 2, a view thereof in section on the line *a* 15 *b* of the preceding figure.

My invention relates to an improvement in game-boards, the object being to produce a simple and cheap device for playing a game of the "Tiddley-Winks" type—which is to 20 say, a game in which the point is to snap a small chip or counter into a certain place or places.

With these ends in view my invention consists in the combination, with a board having 25 its surface divided into compartments or spaces, of one or more revoluble rocking snappers loosely pinned directly to the said surface of the board upon which they rest and each consisting of a short piece of sheet metal 30 having one of its ends formed to normally stand above the said surface, any portion of which may be "covered," so to speak, by properly revolving or training the snappers, which are operated by suddenly impinging 35 their elevated ends upon the board.

As herein shown, the rectangular board *A* is marked off into four circular compartments *B B B B*, consisting of corresponding circles arranged in a square and in contact 40 with each other. I would have it understood, however, that I do not limit myself to any particular way of dividing the surface of the board, which may have any number of compartments of any desired arrangement and 45 form. As herein shown, also, the board is provided in its respective corners with four revoluble rocking snappers *C*, each consisting of a short piece of sheet metal or other suitable material having rounded ends. Each snap-

per has a perforation *c* formed in it to receive 50 a pin *D*, by means of which it is secured to the board, the perforation in the snapper being larger than the shank of the pin, and the head of the pin standing sufficiently above the surface of the board to permit the snapper 55 to rotate freely on the pin and also to be rocked on the same as a center. Each snapper is thus virtually divided by the pin into a long and a short end, the latter being bent upward, so as to normally stand above the 60 surface of the board, being so held by the superior weight of the long end of the snapper. It will be readily understood that if a chip 65 *E* is placed upon the long end of one of the snappers and the short end thereof is struck 70 a sharp blow with the finger that snapper will be quickly rocked on its center and the chip thrown off from its long end and toward the center of the board. If enough dexterity may be commanded, the chip may be thrown 75 to any desired place upon the board with considerable surety, the snappers being thereto rotated or trained to "cover," so to speak, the place upon which it is desired to land a chip. It does not matter how the game is to 80 be played; but it may be suggested that if it be done by counting to throw the chips into one space will count higher than to throw them into another, and so on.

The so-called "snappers" of my improved 85 toy may be likened to miniature catapults, and I am aware that toys having such devices for throwing bean-bags and marbles are old, and I do not, therefore, broadly claim a 90 toy having such a device herein; nor do I broadly claim a game-board having its surface divided off, in combination with a catapult.

Having fully described my invention, what I claim as new, and desire to secure by Letters 95 Patent, is—

The combination, with a flat board having its surface divided into compartments or spaces, of one or more revoluble rocking snappers loosely pinned directly to the said 95 surface of the board upon which they rest and each consisting of a short piece of sheet metal having one of its ends formed to nor-

mally stand above the said surface, against which the said end is suddenly impinged when the snapper is operated, substantially as described, and whereby by properly revolving or training the snappers any portion of the said surface may be covered.

In testimony whereof I have signed this

specification in the presence of two subscribing witnesses.

EDWIN P. McLANE.
